CLAIM

We claim the ornamental design for a vibrational apparatus, as shown and described.

DESCRIPTION

FIG. 1 is a frontal perspective view of a vibrational apparatus.

FIG. 2 is a rear perspective view thereof.

FIG. 3 is a frontal plan view thereof.

FIG. 4 is a rear plan view thereof.

FIG. 5 is a side plan view thereof.

FIG. 6 is a top plan view thereof.

FIG. 7 is a bottom plan view thereof; and,

FIG. 8 is an enlarged perspective view of a handle and console portion thereof, shown separately for completeness of illustration.

The broken lines showing in the drawing disclosure are for illustrative purposes only and form no part of the claimed design.
